UNITED STATES PATENT OFFICE.

GEORGE B. MESS, OF CHARLESTON, WEST VIRGINIA.

MOTOMETER-GUARD.

1,388,190.

Specification of Letters Patent. Patented Aug. 23, 1921.

Application filed September 23, 1920. Serial No. 412,349.

To all whom it may concern:

Be it known that I, GEORGE B. MESS, a citizen of the United States, residing at Charleston, in the county of Kanawha and 5 State of West Virginia, have invented certain new and useful Improvements in Moto-meter-Guards, of which the following is a specification.

The present invention relates to locking 10 devices for automobile accessories, and consists in the combinations and arrangements of elements hereinafter described and particularly set forth in the accompanying claims.

The invention has for its purpose to provide a locking device or guard for securely 15 fastening a moto-meter to the radiator of a car in such a way that the same cannot be stolen therefrom, and wherein the attachment does in no manner interfere with the function 20 of the meter or offer any obstruction to the pouring of water into the radiator.

The invention has for its further purpose to provide a safety device of this character which may be easily and quickly installed on 25 a car without requiring any special skill, and which employs but few parts in its construction, to the end that the same may be manufactured in large quantities and at small cost.

30 The invention is shown by way of illustration in the accompanying drawing, wherein:—

Figure 1 is a front elevational view showing the device in applied position;

35 Fig. 2, an elevational view showing the manner of applying the guard to the radiator;

Fig. 3, a central sectional view of the guard *per se*; and

40 Fig. 4 is a detail view of the holding member and showing the clamping screw mutilated.

Referring to the construction in further detail and wherein like reference characters 45 designate corresponding views in the different figures shown, 5 indicates the radiator of a car having the usual collar 6 providing the pouring opening, which is normally closed by the screw-cap 7; and 8 designates the 50 moto-meter which is mounted on the closure cap 7 in the usual and well known manner.

The locking device or guard consists of a stem or extension 9 having a screw-threaded portion 10 adapted to engage with the 55 threads 11 of the holding member 12, as shown.

The holding member 12 is of tubular structure having a split portion 13 and provided with a plurality of elongated openings 14, and a clamping screw 15 serves for binding 60 the split end of the tube to the threaded portion 10 of the moto-meter stem. To this end said screw 15 has a polygonal head 16 formed with a weakened neck portion 17 whereby said head may be broken off after the clamping screw 15 has been adjusted sufficiently 65 tight to bring the threads 10 and 11 in proper binding relation, as will be understood.

A bolt-like member 18 formed with a head 19 has swiveled connection with the holding 70 member 12 by freely passing through the apertured lower end 20 thereof, and a cross-bar 21 is pivotally connected to the bolt 18 by the pin 22, or in any other suitable manner. Said cross-bar 21 is formed preferably 75 of tubular or U-shaped cross-section to the end of giving the necessary strength with the minimum amount of material. The function of said cross-bar 21 is to prevent the withdrawal of the locking device through the 80 pouring opening of the radiator collar 6 and to effect which said cross-bar normally lies in the cross-wise position shown in Figs. 1 and 3.

For convenience in attaching the device to 85 the radiator of a car the cross-bar 21 is adapted to be brought into the position shown in Fig. 2, when it may be readily inserted through the pouring opening of the radiator, and to secure said cross-bar in 90 normal position after insertion a detent is provided. Said detent consists of a pin 23 normally tensioned by the spring 24 to engage with the aperture 25 formed in said cross-bar; and said pin and spring (23 and 95 24) are contained within the recess 26 formed in the lower end of the bolt member 18. A spring 27 surrounds the bolt 18 between the cross-bar and holding member and has for its purpose to throw the cross-bar into its 100 crosswise or normal position, whence said cross-bar may be engaged and locked in such position by the detent device. To this end the spring 27 seats against the shoulder portions 28 of the cross-bar which acts after the 105 manner of a lever which is moved by the spring.

It will therefore be seen from the foregoing that the device may be easily and conveniently applied to the radiator of a car 110 and being secured to the moto-meter will effectively prevent the removal thereof, inas-

much as any turning to unscrew the moto-
meter will simply give on the swivel connec-
tion 18 and 20; and it will also be obvious
that the device will in no way interfere with
5 the operation of pouring water into the
radiator.

It is obvious that those skilled in the art
may vary the details of construction and ar-
rangement of parts without departing from
10 the spirit of the invention, and the inven-
tion is therefore not limited to such features
except as may be required by the claims.

Having thus described my invention, what
I claim as new is:

15 1. A device of the character described
comprising a holding member for the moto-
meter, a bolt resiliently connected to said
holding member, and a cross-bar for secur-
ing the holding member to the radiator
20 mounted on said bolt, substantially as set
forth.

2. A device of the character described
comprising a holding member for the moto-
meter, a bolt resiliently connected to said
25 holding member, a cross-bar for securing the
holding member to the radiator pivotally
mounted on said bolt, and a detent on said
bolt for securing the cross-bar in locked po-
sition, substantially as set forth.

30 3. A device of the character described

comprising a holding member for the moto-
meter, a bolt loosely connected to the hold-
ing member, a cross-bar pivotally connected
to the bolt for securing the holding member
35 to the radiator, a detent for locking the
cross-bar to the bolt, and a spring inter-
posed between said holding member and the
cross-bar for automatically moving said
cross-bar to locking position, substantially
as set forth.

40 4. A device of the character described
comprising a rigid holding member for the
moto-meter, an inverted T-shaped locking
element adapted for convenient application
45 to a motor radiator, and means for auto-
matically rendering the locking element
rigid when in applied position, substantially
as set forth.

5. A device of the character described
comprising a holding member for the moto-
meter having a downwardly projecting rigid
portion, an inverted T-shaped locking ele-
ment loosely connected to said rigid por-
50 tion and adapted for convenient application
to a motor radiator, and means for auto-
matically rendering the locking element
rigid when in applied position, substantially
as set forth.

In testimony whereof I affix my signature.
GEORGE B. MESS.
